UNITED STATES PATENT OFFICE.

JOSEPH P. GARVER, OF CHARLESTON, ILLINOIS.

RADIATOR-PROTECTOR.

1,399,859.

Specification of Letters Patent. Patented Dec. 13, 1921.

Application filed May 5, 1920. Serial No. 379,132.

To all whom it may concern:

Be it known that I, JOSEPH P. GARVER, a citizen of the United States, and resident of Charleston, in the county of Coles and State of Illinois, have invented certain new and useful Improvements in Radiator-Protectors, of which the following is a specification.

My invention relates to radiator guards or protectors, and more particularly to a guard designed to be applied to a tractor.

It has been found that during the use of tractors in the corn belt, the radiators of the tractors become injured and damaged because as the tractors are driven through the field, the heavy stalks of the corn come in contact with the radiator, which is composed of comparatively soft metal, and results in the radiator becoming damaged by the stalks punching holes into it, or bending the parts of the radiator in such a way as to interfere with the circulation of the water, and rendering it practically useless.

Also, by reason of the draft set up by the fan immediately behind the radiator, leaves and blades of the corn are drawn into the radiator between the coils through which the water is circulated, resulting in the stoppage of the circulation of air, and therefore by lessening the efficiency of the radiator, and oftentimes preventing it functioning sufficiently to properly cool the engine.

It is the object therefore of my invention to provide a guard or protector which can be applied to the front of the radiator, and which will be of sufficient strength to resist the corn stalks or other heavy objects which might injure the radiator by contact therewith, and also to prevent the leaves of the corn from being drawn into the radiator between the coils thereof.

I so construct this radiator guard that it will be simple to manufacture and easy to attach to the tractor. The parts are so arranged as to form a protector which will be light, but of sufficient durability to outlast the life of the tractor.

In forming this guard, I construct the frame of angle bars of the correct size and dimensions to fit snugly over the shell of the radiator of the tractor. I provide two rearwardly projecting rods having hook ends to engage the back edge of the shell of the radiator for securing the guard to the radiator. I then cover this frame with a heavy wire netting.

In this manner I am able to form a shield or guard which can be easily attached to the radiator, and which will in no way interfere with the free circulation of the air therethrough.

Other objects will appear hereinafter in the specification and drawings, in which—

Figure 1 is a perspective view of the front end of a tractor with my invention applied thereto;

Fig. 2 is a transverse sectional view taken on line 2—2 of Fig. 1;

Fig. 3 is a vertical sectional view of my invention and

Fig. 4 is a fragmentary rear elevation thereof.

The numeral 1 indicates the frame of the radiator guard, which is composed of top and bottom pieces 2 and 3 respectively, and side pieces 4. These angle irons are so arranged that one edge of each angle bar projects rearwardly to form a shell-like housing for a purpose to be hereinafter more fully described.

The space between the angle bars is covered by a piece of netting or similar material 5, and this netting is of sufficient dimensions to fit snugly in the shell-like housing formed by the angle bars, and lies against the inwardly projecting sides of the angle bars. This is clearly illustrated in Fig. 2.

In order to secure this netting to the frame 1, and to assist in strengthening the frame, I provide clamping and reinforcing bars 6 which lie along the inwardly projecting sides of the angle bars, as shown clearly in Figs. 2 and 3. These bars 6 bear against the marginal portions of the netting, and as more fully hereinafter set forth, coöperate with the inwardly projecting sides of the angle bars to clamp this netting thereto.

In order to brace the frame 1, and to provide additional support for the netting 5, I provide vertical and transverse tie-rods 7 and 8, respectively. These tie-rods are formed with eyes 9 and are secured in place by bolts 10, passing through the inwardly projecting sides of the angle bars, the netting 5, the clamping and reinforcing bars 6, and then through the eye 9 of these tie-rods 7 and 8. Nuts 11 are screw-threaded on the ends of bolts 10 for securing these bolts in place. Thus it will be seen that I am able to tie together the entire structure by these bolts 10, and in doing so, provide

means for attaching ends of the tie-rods 7 and 8. Four bolts 12 pass through the overlapping corners of the angle bars and through the clamping and reinforcing bars 5 6, and are secured in place by nuts 13.

The radiator shell of the tractor is indicated by A, and has formed on its front face projections B at the top and bottom thereof, and is provided with rearward projections 10 C. All of these parts are features of the shell of the radiator of the tractor, and are illustrated for the purpose of showing means of positioning my invention thereto.

As clearly illustrated in Figs. 1 and 3, the 15 shell-like housing formed by the angle bars fits over the projections B of the shell of the radiator. In order to retain the guard in place upon the radiator, I provide rearwardly projecting securing rods 14, positioned intermediate the sides of the frame. These rearwardly projecting rods 14 are provided with hook ends 15, which are adapted to extend around the projections C 20 of the radiator shell. The other ends of the rods 14 extend through the side bars 4 of the frame, and are provided with clamping nuts 15. In applying the guard to the radiator, the same is positioned over the projections B, and the rearwardly projecting rods 30 14 hooked over the projections C and the nuts 15 tightened, thereby securely fastening the protector upon the front of the radiator.

The shell-like housing which is formed by 35 the angle bars, engages the projections B extending from the shell of the radiator, thereby preventing vertical or lateral displacement of the same. The rearwardly projecting hooks which are formed to engage the 40 projections C of the radiator shell, coöperate with the housing to securely position this guard upon the radiator. With the protector in this position, objects which would ordinarily come into contact with the radiator will now contact this guard, and hence 45 the damage to the radiator, which usually results, will be prevented inasmuch as the guard is of sufficient strength to resist the force of the corn stalks or other objects in 50 the path of the tractor. Also the leaves of the corn and other light material, which would ordinarily be drawn into the radiator, between the coils thereof, will be prevented from doing so by reason of the nature of

the netting or other material which covers 55 the frame.

Various changes and modifications in the form and structure of my invention may be resorted to without departing from the spirit and scope thereof, and I particularly re- 60 serve this right.

Having thus described my invention, what I claim is:—

1. A guard for tractor radiators provided with forwardly and rearwardly extending 65 projections, said guard comprising a frame formed of angle bars, a perforate material covering said frame, securing means for said perforate material engaging the margin thereof, tie-rods spanning said frame 70 and lying adjacent said perforate material, means for uniting the tie-rods to said frame, means secured to said frame for engaging the rearwardly extending projections of the radiator, said frame being adapted to engage 75 the forwardly extending projections of the radiator.

2. A radiator guard comprising a frame composed of angle bars, the sides thereof projecting inwardly and rearwardly of said 80 frame and a perforate material covering said frame, tie-rods spanning said frame, reinforcing and clamping bars positioned against the marginal portion of said perforate material to hold the same against the 85 inwardly projecting sides of said angle bars, bolts for uniting said reinforcing and clamping bars to said frame and for securing said tie-rods and perforate material to said frame, and means for securing said frame to a tractor 90 radiator.

3. The combination with a tractor radiator provided with forwardly and rearwardly extending projections, of a removable guard, said guard comprising a frame 95 forming a shell-like housing, said frame being formed of angle bars, perforate material covering said frame, tie-rods spanning said frame, reinforcing and clamping bars for said frame, means for uniting them to said 100 frame, rearwardly projecting rods adapted to engage the rearwardly extending projections of said radiator, while the shell-like housing engages the forwardly projecting extensions of said radiator, substantially as 105 described.

JOSEPH P. GARVER
